UNITED STATES PATENT OFFICE.

JOHN O. WEISSE, OF LA CROSSE, WISCONSIN.

FLUSH CASEMENT CATCH.

Application filed August 25, 1924, Serial No. 734,062. Renewed April 17, 1926.

This invention relates to window casement hardware and more particularly to catches for holding multifold swinging sash in open position.

5 The object of the invention is to provide a casement catch made on the gravity lever principle whereby a swinging sash is held in open position until manually released.

10 With the foregoing and other objects in view which will appear as the description proceeds, the invention resides in the combination and arrangement of parts and in the details of construction hereinafter described and claimed, it being understood 15 that changes in the precise embodiment of the invention herein disclosed, may be made within the scope of what is claimed without departing from the spirit of the invention.

In the accompanying drawings:

20 Figure 1 represents a horizontal section of a three-sash window equipped with this improved fastener the sash being shown closed in full lines and open in dotted lines.

25 Fig. 2 represents a front elevation of the fastener with the locking catch shown in section.

Fig. 3 is a detail sectional view taken on the line 3—3 of Fig. 2.

30 Fig. 4 is a side elevation of the catch for locking the sash in closed position; and

Fig. 5 is a detail perspective view of the catch for locking the sash in open position.

In the embodiment illustrated a window frame is shown at F in which is mounted 35 three sash 1, 5, and 10 the middle sash 5 being stationary and held in closed position by screw 6. The sash 1 and 10 are hingedly mounted on the opposed side edges of sash 5 sash 10 being secured to sash 5 by short 40 butt hinges 11 while sash 1 is swingably mounted on the opposed edge of sash 5 by long butt hinges 2 so that when opened sash 10 will swing over sash 5 and sash 1 will swing over sash 10 as shown in dotted lines 45 in Fig. 1.

These sash when opened are held by the fasteners 3 and 12 constituting this invention and which are exactly alike hence one only will be described in detail.

50 Each fastener comprises a base plate 13 screwed or otherwise secured to the inner face of the sash in connection with which it is to be used. This plate 13 has an outwardly bulged apertured central portion 14 on which is pivotally mounted a swinging latch member 15 the bulged portion 14 oper-

ating to hold the latch spaced from the plate 13 to permit it to swing freely relatively thereto.

The swinging latch or lever 15 is preferably made wider at one end than the other and to the wide end thereof is hingedly connected a hand grip 16 the narrow end 17 being designed to engage a notch in the lower edge of a catch 20 carried by the sash 65 to which the lever carried sash is to be locked.

Two catches 20 and 25 are here shown mounted respectively on the sash 5 and on the sash 10 which are designed to be engaged by the latches 13 and 3 respectively when the sash 10 and 1 are swung in open position.

The catches 20 and 25 are exactly alike and each comprises an attaching plate 21 apertured as shown at 22 for the passage of the fastening elements and provided at one edge with a laterally extending plate 23 having notches 24 in its opposite ends with which notches the latch 15 is designed to 80 engage.

By mounting the handles 16 on the wider or heavier end of the lever-like latch 15 this end is made heavier so that it will drop downward by gravity and cause the smaller 85 end 17 to swing upwardly into locking engagement with the notch 24 in the lower end of the catch arm 23.

It will thus be seen that when sash 10 is 90 swung inwardly into the dotted line position shown in Fig. 1 the latch 13 carried thereby will engage the catch 20 the handle 16 being folded in the position shown in Fig. 1.

The sash 10 must be made about three- 95 sixteenths of an inch narrower than the other two to clear the wide butt hinges 2 of the sash 1 when said sash is opened.

When the sash 1 is swung into open position the latch 3 carried thereby will engage 100 catch 25 on sash 10 and thereby securely lock sash 1 in open position.

Mounted on the window frame F at opposite sides thereof are catch members 30 shown in the form of apertured plates having arms 31 extending from one edge thereof in the same plane as the body of the plate with a recess 32 formed between the arm and the plate and which is designed to receive the latches carried by the sash 1 and 105 110 when said sash are in closed position (see Fig. 1).

From the above description it will be seen that the swinging sash 1 and 10 may be opened inwardly and folded one on the other over the stationary central sash 5 and be held in this position by interlocking engagement of the latches 3 and 13 with the catches 25 and 20 respectively.

When the sash 1 and 10 are closed they are swung into the full line position shown in Fig. 1 and the latch members 3 and 13 carried thereby will engage the catch members 30 the smaller ends 17 swinging into the recesses 32 of the catches 30 and being held by gravity in this position.

15 Various changes in the form, shape, proportion and other minor details of construc-

tion may be made without departing from the principle or sacrificing any of the advantages of the claimed invention.

I claim:—

20 A fastener of the class described comprising a lever, a handle portion hingedly connected to one end of the lever and adapted to be swung to a position to overlie the lever, a catch having a notch to receive one 25 end of the lever, and said handle portion adapted to overbalance the lever to move the lever into engagement with the catch.

In testimony that I claim the foregoing as my own, I have hereto affixed my signature.

JOHN O. WEISSE.
